HANDLE GUARD FOR WELL CASING
ELEVATORS

Herbert E. Grau, Los Angeles, Calif., assignor to
Byron Jackson Co., Los Angeles, Calif., a corporation of Delaware

Application August 24, 1934, Serial No. 741,257

6 Claims. (Cl. 294—90)

This invention relates to well casing elevators, such as are supported on elevator links, and which engage the collar on well casing or drill piping in deep wells for raising and lowering the same. This elevator is of a split collar type adapted to be swung open to receive the upper end of the casing or tube string when being attached to the same. The invention relates particularly to that type of elevator commonly called a "center latch" elevator, because it comprises a pair of semicircular casing-encircling sections or doors hinged together at the back and provided with a latch member at the front.

It has been common practice to provide "center-latch" elevators with outwardly and forwardly projecting "horns" or "horn" handles, such as are shown in United States Patent No. 1,468,589, issued September 18, 1923, to W. W. Wilson. While these handles have been very convenient for opening and closing the elevator, they have had the disadvantage that the operator is apt to pinch his hand or fingers between the handles and elevator links when opening or closing the elevator.

One of the objects of the present invention is to provide a construction which will overcome this objection; also to provide handles for such an elevator which will operate effectively for opening and closing the elevator, and which will provide a good hand-hold for the hand that is applied to the handle for opening and closing the elevator.

A further object of the invention is to construct the guard in such a way that the use of the guard does not unnecessarily increase the length of the handle.

A further object of the invention is to construct the handles so that they will have ample strength to prevent their being accidentally broken off.

Further objects of the invention will appear hereinafter.

The invention consists in the novel parts and combinations of parts to be described herein-after, all of which contribute to produce an efficient handle guard for well casing elevators.

A preferred embodiment of the invention is described in the following specifications, while the broad scope of the invention is pointed out in the appended claims.

In the drawings:

Figure 1 is a top plan view of an elevator embodying my invention and showing the elevator links in cross section on a plane just above the elevator.

Figure 2 is a front elevation of the elevator illustrated in Figure 1, showing the lower portions of its supporting links broken away.

Figure 3 is a side elevation of the elevator illustrated in Figures 1 and 2, but omitting the supporting links for the same.

Referring more particularly to the parts, the elevator 1 preferably consists of two gates or doors 2 and 3 which are connected together by a hinged joint at the back by means of a substantially vertical hinge pin 4. These gates or doors 2 and 3 cooperate to form a split collar and are provided with diametrically disposed meeting faces 5 which come together in the closed condition of the elevator and the adjacent faces of the doors 2 and 3 are provided with arcuate semicircular faces 6 which cooperate to form an opening or bore to fit accurately to the diameter of the pipe or casing that is to be suspended in the elevator by engaging a collar on the upper end of the pipe. Adjacent the free end 7 of each door, I provide a forwardly projecting elongated handle 8 and these handles are preferably inclined outwardly although they are preferably disposed in a substantially horizontal plane.

In other words, these handles diverge from each other, as viewed in plan (see Fig. 1). Each door is provided with a laterally and forwardly projecting ear 9 and in the present instance each of these ears is diverted so as to present an upper portion or lug 9a and a lower portion or lug 9b between which a recess 10 is formed to receive the lower end of the supporting link 11, at that side of the elevator. The recess 10, in the present instance, is closed by a movable latch bar 12, which is attached by a pivot 13 to the lower lug 9b and secured by a bolt 14 to the upper lug 9a. This locking bar 12 is disclosed in a copending application Serial No. 741,249, filed August 24th, 1934, by Chester A. Lundeen.

Near the outer end of each handle 8 I provide a handhold 14a beyond which the handle preferably terminates in a "pull" or "knob" 15 which is preferably of substantially spherical form. Between each handhold 14a and its adjacent link 11 I provide a guard member 16 and each of these guard members is preferably formed of a tapered spur, the longitudinal axis of which is inclined with respect to the longitudinal axis of the handle carrying the guard. In other words, these guards project laterally and outwardly on the outer sides of the handles and their inner sides are preferably formed with convex faces 17 lying near the face of the adjacent link. On the outer

side edge each guard 16 is preferably formed with a concave face 18, as viewed in plan.

By employing the concave faces 18, the guard is cut back toward its edge and this has the effect of giving an increased length for the adjacent handhold 14a for a given length of handle.

The handles 8 are preferably formed integral with their corresponding gates 2 or 3, and, in order to strengthen these handles and prevent their being broken off accidentally, I prefer to provide a tapered rib 19 on the underside of each handle. The inner end of this rib, of course, unites integrally with the corresponding door 2 or 3. Each rib is so tapered that it dies out on the handle near the root of the guard 16. In Fig. 1 the dotted lines 20 and 21 indicate the outlines of this rib, as viewed in plan.

The elevator is preferably held in its closed position by means of a latch 22 (see Fig. 2), which is secured to a rocking pin 23 provided with a spring 24, exerting its force in a direction to hold the head of the latch 22 in a socket 25 on the opposite door or gate. This latch is disclosed in the copending application Serial No. 25 741,403, filed August 25th, 1934, by Chester A. Lundeen.

It will be evident that in using this elevator the doors 2 and 3 can readily be swung open or closed by seizing the handholds 14a and pulling them in the proper direction. It will also be evident that the guards 16, located as they are between the handholds and the links 11 prevent the possibility of the fingers of the hand from being pinched against the adjacent faces 35 of the links 11.

It is understood that the embodiment of the invention described herein is only one of the many embodiments this invention may take, and I do not wish to be limited in the practice of the invention, nor in the claims, to the particular embodiment set forth.

What I claim is:

1. In a well casing elevator to be supported on elevator links, the combination of a pair of relatively movable doors connected together at the rear side of the elevator and adapted to close about the well casing, a latch connecting the front ends of said doors, each door having an elongated outwardly extending handle adjacent the free end of the door, each handle having a handhold located toward its outer end, and having a guard member in the form of a spur projecting out from the handle and located between the handhold and the adjacent link.

2. In a well casing elevator construction, the combination of a pair of supporting links, an elevator having a pair of doors hinged together at the rear and having outwardly and forwardly extending ears at the sides supported on the said links respectively, each of said doors having an elongated outwardly extending handle adjacent its forward end with a handhold adjacent the outer end thereof, and a guard on each handle projecting laterally and outwardly therefrom be-

tween the handhold and its adjacent link, and limiting relative movement of the links toward the handholds.

3. In a well casing elevator to be supported on elevator links, the combination of a pair of relatively movable doors connected together at the rear side of the elevator and adapted to close about the well casing, a latch across the front ends of said doors, each door having an elongated handle extending forwardly in an inclined direction, with a handhold adjacent the outer end of the handle, and a guard on each handle in the form of an integral spur projecting laterally from the outer side of the handle between the handhold and the adjacent link, said spurs operating to limit the relative movement of the links toward said handholds.

4. In a well casing elevator to be supported on elevator links, the combination of a pair of relatively movable doors connected together at the rear side of the elevator and adapted to close about the well casing, a latch across the front ends of said sections, each door having an elongated outwardly extending handle adjacent the free end of the door, each handle having a handhold located toward its outer end, with a guard member located between the handhold and the adjacent link, each guard being in the form of an integral spur located so that its longitudinal axis is inclined with respect to the longitudinal axis of the handle.

5. In a well casing elevator to be supported on elevator links, the combination of a pair of relatively movable doors connected together at the rear side of the elevator and adapted to close about the well casing, a latch across the front ends of said doors, each door having an elongated outwardly extending handle adjacent the free end of the door, each handle having a handhold located toward its outer end, with a guard member located between the handhold and the adjacent link, each guard being in the form of an integral spur located so that its longitudinal axis is inclined with respect to the longitudinal axis of the handle, each handle being integral with its corresponding door and having an integral rib on its underside, said rib having its greatest depth at the door and terminating at its outer end adjacent the handhold.

6. In a well casing elevator to be supported on elevator links, the combination of a pair of relatively movable doors connected together at the rear side of the elevator and adapted to close about the well casing, a latch across the front ends of said doors, said doors having outwardly projecting diverging handles with handholds thereon near their outer ends, each handle having a guard in the form of an integral spur on its outer side located between the handhold and the adjacent link, each spur having a concave form on its outer side, thereby giving an increased length for the handhold.

HERBERT E. GRAU.
